LOUIS L. LEVENE, OF MERRICK, NEW YORK

DOORCHECK

Application filed May 14, 1932. Serial No. 611,297.

Various devices have been devised for automatically closing doors with regulated motion to avoid slamming of the door against the door jamb. Such devices have commonly been termed door checks. The majority of door checks heretofore devised and in use are rather large and expensive because they include complicated mechanism for transmitting the energy expended in opening the door to a resilient member, in which part of the energy is stored in the form of potential energy, and transposing that stored energy, when released, into closing movement of the door. Commonly, these door checks are large and cumbersome, requiring a large housing to enclose the mechanism, and they are fastened to the doors, where they are at all times visible from the interior of the room. In certain instances, door checks have been devised whereby the check may be concealed in the floor beneath the door. These latter types of door checks are, however, complicated and expensive, and involve a high installation charge because of the necessity of providing a pocket below the door to receive the check mechanism.

By my invention, I have devised a door check having cooperating parts adapted to be included in the door and door frame and which is simple in construction, comparatively inexpensive to manufacture, and may be concealed within the door. The device of my invention eliminates the necessity of using the common link motion for the transmission of angular movement of the door into motion in such direction as to store up potential energy in a resilient member and transmitting that energy to the door for closing the door. In accordance with my invention, I provide a door check in which angular movement of the door is directly transposed, without the use of intermediary link mechanism, into straight line motion of the operative mechanism of the door check. The door check effects the closing of the door by straight line action of the check mechanism and thus, eliminates the necessity of complicated and expensive transposing mechanism common in the usual type of door check.

A feature of my invention is the fact that it is equally applicable to doors that swing in two directions.

An advantage of the door check of my invention is the fact that the door closer mechanism becomes inoperative when the door is opened beyond a certain angular position.

Another feature of my invention is the fact that the closer action of the door check may be restrained at certain definite angular positions at which it may be desirable to maintain the door in an open position.

Specifically, the door check of my invention essentially includes two cooperating sections, one of which is adapted to be mounted in the door, and another adapted to be mounted in the door frame. The section mounted in the door comprises an elongated cylinder, preferably mounted in the rail of the door, longitudinally thereof. Within this cylinder there is reciprocally mounted a piston to which is secured a piston rod that extends through the end of the cylinder adjacent the hinged edge of the door. Surrounding the piston rod is a convolute spring which acts between an adjustable abutment within the cylinder and the piston, and resiliently urges the piston in a direction within the cylinder to withdraw the piston rod into the cylinder. At the other end of the cylinder, there is a fluid reservoir which communicates with the cylinder through two passages. One of the passages is provided with a check valve that permits a free flow of fluid from the reservoir into the cylinder and prevents the fluid from flowing from the cylinder through the passage back to the reservoir. The other passage is of smaller diameter and includes a branch passage which has conical walls. A complementary conical plug, accessible from outside the cylinder, cooperates with the conical passage. In this way the action of the spring in pressing the piston towards the reservoir end of the cylinder is restricted so as to prevent rapid movement of the piston in the cylinder under the action of the spring. The plug of course may be adjusted to afford greater or less resistance to the flow of fluid through

the passage in accordance with the desired freedom of operation of the door to which the door check is applied.

The section of the door check adapted to be mounted in the door frame consists of a two-part fixture which is mounted in the stile member of the door frame or, in the case of a door that swings in two directions, in the rail of the door frame. One part of this fixture has formed therein an involute cam track with the hinge of the door as the point about which the involute is described. On the end of the piston rod extending through the cylinder, there is mounted a cam follower which extends into the involute cam track and engages the side walls thereof. As a door, containing a door check as described above, is moved angularly about its hinges to open the door, the ever increasing radius of curvature of the involute cam track transposes the angular movement of the door directly into longitudinal movement of the piston rod and causes the piston rod to be withdrawn from the cylinder, moving the piston within the cylinder against the action of the convolute spring and thus storing up potential energy in the form of the compressed spring. As the door is released the force exerted on the piston by the spring is transmitted to the cam follower which presses against the side of the cam track. Due to the curvature of the cam track, the force so exerted is broken up into components, one of which components acts tangentially to the cam track at the point of contact of the cam follower. This tangential force causes angular movement of the piston rod which is transmitted to the door. As the piston moves in the cylinder on opening the door, fluid flows from the reservoir at the end of the cylinder through the check valve and into the cylinder. As the spring acts to close the door, the check valve closes the unrestricted passage between the reservoir and the cylinder and the fluid is forced to return to the reservoir through the restricted passage, thus checking and slowing down the movement of the piston under the action of the spring.

The other part of the fixture which is secured in the door frame consists of an arm that is pivotally secured to the fixture. This arm has a notch formed therein which coincides with the cam track in the fixture, and the end of the cam track is formed by this notch in the arm. As the door is opened to a position in which the cam roller on the piston rod enters the notch in the arm, the door check becomes inoperative and upon further opening movement of the door, the arm swings about its pivot, so that in all positions beyond that position in which the cam follower on the piston rod enters the notch in this movable arm, the closure action of the door check is rendered inopera-

tive, and the door may be maintained in an open position.

The invention will be more clearly understood from the following particular description of the embodiments thereof shown in the accompanying drawings in which:

Fig. 1 is a fragmentary elevation, partly in section, of a door and door frame in which a door check embodying my invention is mounted;

Fig. 2 is a fragmentary, sectional plan taken through the axis of the door check;

Fig. 3 is a fragmentary, sectional elevation of the door, showing the door check partly in section;

Fig. 4 is a fragmentary, transverse, sectional elevation of the door, taken on the line 4-4 of Fig. 3;

Fig. 5 is a fragmentary plan of a door adapted to swing in two directions and having a door check of my invention mounted therein; and

Fig. 6 is a fragmentary, sectional elevation of the same.

In the drawings, there is illustrated in Figs. 1 to 4 inclusive, a sheet metal door construction of the usual type. As shown in the drawings, the door 1 is mounted in a door frame having the usual stile and rail members 2 and 3 respectively. The door is pivotally mounted in the door frame by means of the usual pivot hinges 4. Within the door, preferably in the upper rail member as shown in the drawings, there is mounted one section of a door check which section includes an elongated cylinder 5 of a diameter less than the thickness of the door. This cylinder is mounted within the door parallel to the rail member and with one edge thereof in the plane of the hinged edge of the door. The ends of the cylinder are internally threaded and one end receives a reduced externally threaded end of a built-up auxiliary cylinder 6 which includes the cast end that is received in the cylinder 5 and a cup-shaped sheet metal section 6a secured thereto. The auxiliary cylinder forms a fluid reservoir, and the end 7 of this fluid reservoir forms a partition wall between the cylinder and the reservoir. Through the partition wall 7, there is a passage 8 sufficiently large to permit a free flow of fluid therethrough. On the outer surface of the partition wall there is pivotally mounted a flap valve 9 which is adapted to lie against the partition wall and cover the passage 8. The flap valve is mounted against the outer surface of the partition wall so that a free flow of fluid is permitted from the reservoir to the cylinder, while a reverse flow, that is, a passage of fluid from the cylinder to the reservoir is checked by the flap valve which, in its normal position and when pressure is exerted upon it from the cylinder, lies against

the partition wall and covers the passage 8. A second passage 9' is provided in an extension that extends inwardly of the reservoir from the partition or end wall 7. This passage 9' has a radial branch passage 9'a at an angle thereto and extending through the extension. The walls of the passage 9'a are conical and cooperate with a conical plug 10. Through this passage 9 and the branch passage 9'a, fluid may flow from the cylinder into the reservoir. However, in passing from the cylinder into the reservoir, the fluid must pass through the branch passage 9'a, and when the plug 10 is in position, the flow of the fluid is restricted. By inserting the plug different amounts into the passage 9'a, the flow of fluid in returning to the reservoir, is more or less restricted, and consequently it will require a force in proportion to the restriction to force the liquid from the cylinder into the reservoir. Also through this extended passage 10 there is an opening for replenishing the fluid in the reservoir. This inlet opening is sealed or closed by a threaded plug 11 which may be removed for introducing fluid into the reservoir.

Within the cylinder 5 there is mounted a piston 12. The piston 12 has a reduced portion 13 on which is mounted a pair of reversed, cup-shaped, leather packing members. The cup-shaped packing members are held in place on the piston between a washer 14 which abuts against the shoulder formed by reducing the diameter of the piston and a nut 15 threaded on to the end of the piston. These cup-shaped leather washers form a fluid-tight slidable connection between the piston and the inner surface of the cylinder. To this piston there is secured a piston rod 16, one end of which is threaded into a recess 17 formed in the end of the piston. The piston rod extends longitudinally of the cylinder and through the end of the cylinder at the hinged edge of the door. The outer end 18 of the piston rod is enlarged and there is a radial pin 19 extending through the enlarged end or head and secured thereto. On this pin, there are mounted cam followers 20, one on either side of the piston rod.

The internal threads in the end of the cylinder at the hinged edge of the door engage external threads formed on an abutment member 21 which fits within the cylinder. The abutment has a reduced annular portion and between the shoulder 22, formed by reducing the diameter of the abutment, and a shoulder 23, formed on the piston 12, there is mounted a convolute spring 24 which surrounds the piston rod. This spring acts between the abutment 21 which is stationary with respect to the cylinder and the piston 12 and resiliently urges the piston towards the reservoir end of the cyl-

inder, that is, in a direction to draw the piston rod into the cylinder. The abutment 21 is provided on its outer end with recesses 25 which are adapted to receive a wrench for adjusting the abutment in the cylinder 21 and varying the force with which the spring 24 acts upon the piston 12. The end of the cylinder through which the piston rod extends is closed by an externally threaded cap 26 that engages the internal threads on the cylinder. This cap is provided with a hub 27 through which the piston rod extends. The cap also has a pair of recesses or openings therethrough located similar to the recesses 25 in the abutment 21 so that the same wrench may be used for removing the cap and adjusting the abutment.

Cooperating with the section of the door check above described, there is another section which consists of a fixture 28 which is mounted on the stile of the door frame in the same plane as the cylinder of the door check. This fixture extends through the stile member and on one side of the door, that is, the fixture is L-shaped in plan. In this fixture there is cut a groove 29 and in the walls of this groove there are cut opposed cam recesses 30. These cam recesses are adapted to receive the cam followers 20 mounted on the radial pin extending through the enlarged end of the piston rod. The cam grooves or cam tracks are involute curves, the base circles of which are described about the center of the hinge connection between the door frame and the door. The involute curved cam tracks present an ever widening cam surface in an angular direction. These cam tracks cooperate with the cam followers and the piston rod to move the piston rod longitudinally of the cylinder when the cylinder is moved angularly with the opening and closing of the door.

The fixture also includes an L-shaped arm 28'a which is pivotally secured to the fixture by means of a hinge 33. This arm forms one side of the L-shaped fixture, the side adjacent the door. In this arm there is formed a notch 34 which forms the end of the cam track in the fixture. This notch is such that the force exerted on the cam follower by the spring 23 is not resolved into a tangential component so that when the cam follower enters this notch, the closure action of the check is rendered inoperative. On opening the door further than the position in which the cam followers entered the notch in the arm, the arm swings about its hinge connection to the fixture, and in all positions in which this arm swings about its hinge, the closer device is rendered inoperative. In the door check shown in the drawings, the cam followers on the piston rod engage this arm when the door is opened at an angle of approximately 110°.

In Figs. 5 and 6 I have illustrated the door

check described above as it is used in connection with a double swinging door. In this construction the door check is identical with that described above, with the exception that the extended end of the piston rod, extending through the end of the cylinder, is bent at an angle of 90° to form an angular extension 31 on which the cam follower is mounted, and the cam track fixture 28' 10 is mounted in the rail of the door frame rather than in the stile. This cam track is a double cam track being made up of two involute curves, one on either side of the central, vertical, longitudinal plane of the door, and the two tracks being connected together so as to permit free angular movement of the piston rod in either direction. The curve is of course symmetrical on both sides of the vertical, central plane of the door.

The operation of the door check above described is as follows: As the door is opened, that is, moved angularly with respect to the door frame and about its pivotal connection thereto, the cam followers 20, secured to the piston rod, move along the cam track formed in the fixture 28. As this cam track is of an ever increasing radius of curvature, the piston rod will be withdrawn to a greater or less extent, depending upon the angular movement of the door. As the piston rod is withdrawn by the action of the cam track, the piston will be moved in the cylinder against the action of the spring 24. 25 The piston moving in the cylinder creates a reduced pressure at the reservoir end of the cylinder and fluid flows from the reservoir into the cylinder through the passage 8, swinging the flap valve 9 about its pivot. 30 When the door is released, the potential energy stored up in the spring 24, by virtue of the movement of the piston against the spring and the compression of the spring between the abutment and the piston, is released and acts upon the piston with a force sufficient to move the piston in the direction of the reservoir end of the cylinder. This force is transmitted through the piston rod to the cam followers 20 which are 35 pressed against the wall of the cam track. The force between the cam follower and the wall of the cam track is, by virtue of the curvature of the cam track, broken up into components, one component of which acts tangentially of the curved surface of the cam track, and in a direction to move the piston rod angularly, thus closing the door. This closing action of the door is restricted by the incompressible fluid which has passed 40 through the passage 8 from the reservoir into the cylinder. The pressure on the fluid exerted by the spring pushing the piston towards the reservoir end of the cylinder closes the flap valve and in order for the 45 fluid to return to the reservoir, it must pass

through the passage 9. Only a small portion of the fluid can pass through this passage at a time and consequently the movement of the piston towards the reservoir end of the cylinder is restricted in accordance 70 with the resistance placed upon the fluid passing through the passage 9. As heretofore described, the restriction to the flow of the fluid may be varied by adjusting the plug 10 in accordance with the desired speed 75 of the pistons. The resistance to the flow of fluid checks the action of the door closer so as to prevent the door from slamming against the door jamb.

By cutting notches in the walls of the cam track, as indicated at 35, the door may be held open against the closing action of the check in various positions, for the force exerted will not be broken up into the necessary components.

From the above description of my invention, together with the explanation of the operation of the door check, it will be obvious to those skilled in the art that I have produced a door check in which all the action or mechanical movement is a straight line movement. The importance of this straight line movement is that it accomplishes a reciprocating movement of the controlling piston of the door check without the use of the usual complicated and expensive link motions characteristic of the common door checks now in use; it results in a door check that may be completely concealed within the door, and it provides a construction of a door check that is comparatively inexpensive.

It is obvious that various changes may be made by those skilled in the art in the details of the embodiment of my invention illustrated in the drawings and described above within the principle and scope of the appended claims.

I claim:

1. A door check comprising a cylinder adapted to be mounted on a door, a piston reciprocally mounted within the cylinder, resilient means acting upon said piston to urge the piston toward one end of the cylinder, means adapted to cooperate with the piston rod for transposing longitudinal movement thereof into angular movement of the cylinder, means for rendering said transposing means inoperative in certain angular positions of the cylinder, and additional means for restraining operation of the check mechanism beyond a certain angular position of the cylinder.

2. A door check comprising in combination, a cylinder adapted to be mounted on a door, a piston reciprocally mounted within the cylinder, resilient means within the cylinder and acting upon the piston to urge the piston towards one end of the cylinder, a piston rod secured to the piston and extend-

ing through the cylinder, and a fixture adapted to be mounted on the door frame and having a cam track therein cooperating with the piston rod for transporting longitudinal movement of the piston rod into angular movement of the cylinder, said cam track having a notch therein for interrupting the transposing action at a particular angular position of the cylinder.

10 3. A door check comprising in combination, a cylinder adapted to be mounted on a door, a piston reciprocally mounted within the cylinder, resilient means within the cylinder and acting upon the piston to urge the piston towards one end of the cylinder, a piston rod secured to the piston and extending through the cylinder, a fixture adapted to be mounted on the door frame and having a cam track therein cooperating 15 with the piston rod for transposing longitudinal movement of the piston rod into angular movement of the cylinder, said cam track having a notch therein for interrupting the transposing action at a particular angular position of the cylinder, and an arm 20 pivotally secured to said fixture and having a notch therein in alignment with the cam track.

25 4. A door closer and check comprising in the assembled position a fixture mounted on a door frame and a closer and check mounted on the door and including a housing and a longitudinally movable member extending through the housing and into the fixture, said fixture and movable member being directly connected and the fixture including

means for transposing angular movement of the housing into longitudinal movement of the movable member in one direction and longitudinal movement of the movable member in the opposite direction into angular movement of the housing, and closer and check mechanism within the housing including means acting upon said movable member tending to move it in the direction to cause angular movement of the closure 70 mechanism and retarding means for retarding the movement of the movable member.

5. A door closer and check comprising in the assembled position a fixture having an involute cam track therein mounted on a door frame, a closer and check including a cylindrical housing mounted within the door and an axially movable rod extending through one end of the cylindrical housing and into the fixture, a cam follower on the 80 movable rod engaging the faces of the cam track in the fixture, and cooperating with the cam in the fixture to transpose angular movement of the cylindrical housing into longitudinal movement of the rod in one direction and longitudinal movement of the rod in the opposite direction into angular movement of the cylindrical housing, and closer and check mechanism within the cylindrical housing including means acting 85 upon the rod tending to move it in the direction to cause angular movement of the closure mechanism and retarding means for retarding movement of the movable member.
